UNITED STATES PATENT OFFICE.

JOHN E. SUMPTER, OF ST. PAUL, MINNESOTA.

SIGNAL DEVICE.

Application filed December 21, 1917. Serial No. 208,260.

To all whom it may concern:

Be it known that I, JOHN E. SUMPTER, a citizen of the United States, residing at St. Paul, in the county of Ramsey and State 5 of Minnesota, have invented a new and useful Improvement in Signal Devices, of which the following is a specification.

My invention relates to signal devices the primary object of which is in providing an 10 electrically operated signal device which is released into signalling position or raised out of signalling position by means of a single electro-magnet which is connected to a source of electrical energy and operated 15 by a single circuit closing switch or push button.

A further object is in providing a signal 20 arm with a signal light which is turned on automatically when the arm is released into signalling position.

It is also an object in providing a device 25 which is of extremely simple construction composed of a small number of parts and peculiar features of construction which will be hereinafter more fully described and claimed.

In the drawing forming part of this specification:

Figure 1 is a side elevation of the 30 signalling device partly broken away and having half of the enclosing casing removed.

Figure 2 is a side elevation of the signalling device with half of the casing removed and the signal arm shown in signalling position also illustrating diagrammatically part of the electric wiring.

Figure 3 is a plan view of the device part of which is illustrated in cross section.

Figure 4 is a section on the line 4—4 of 40 Figure 1.

Figure 5 is a perspective of an alternative construction of signalling device part of the electric wiring being illustrated in diagrammatic form.

45 Figures 6, 7, 8 and 9 illustrate positions of the signalling device of the alternative construction illustrated in Figure 5.

Figure 10 is a side elevation of an alternative form of the signalling device partly 50 broken away having one-half of the enclosing casing removed and illustrating the electric wiring in diagrammatic form.

Figure 11 is a side elevation similar to

Figure 10 illustrating the signalling arm in signalling position.

55

Figure 12 is a segmental section taken on the line 12—12 of Figure 11.

In the drawing, A represents a signalling device which is so constructed as to be used primarily for automobiles, it being evident 60 however, that the signal can be used for other purposes without departing from the spirit of the invention.

The signalling device A has a signal arm 1 which has secured to its outer free end, the 65 light casing 2. The signal light casing 2 is formed circular and of a disk shape, having large circular openings 3 on either side of the casing which are closed by glasses 4 which may be transparent, red, green or any 70 other suitable color. The signal electric light D illustrated in Figure 2 in dotted outline, is held in any convenient manner inside the casing 2 centrally between the glass sides 4. The openings 3 are very large, 75 thereby leaving only a small circular shell or band like portion 5 which forms the head of the casing portion 2 and in which the glasses 4 are held.

The signal arm 1 is rigidly secured to a 80 spider frame 6, having flat web like spokes 7, which is pivotally secured on the shaft 8. The shaft 8 is rigidly secured to and between the sides 9 and 10 of the casing 11.

The casing 11 is formed in two halves 85 9 and 10, the rear portion 12 of which is cylindrical in shape and adapted to enclose or form a cover for an electro-magnetic coil B. Upper flanges 13 and lower flanges 14 are formed on the casing 11 and are adapted to 90 hold the portions 9 and 10 together by means of the bolts 14'.

The spider frame 6 is formed with a segmental circular outer flange 15 which is adapted to fit in the groove 16 formed in the 95 forward part 17 of the casing 11 so that the outer surface of the flange 15 will lie flush with the outer circular surface 18 of the casing which extends on either side of the flange 15. Thus the upper portion of the 100 end 17 of the two halves 9 and 10 of the casing is formed with a slot 19 in which the frame 6 and signal arm 1 can rotate. The lower part of the portion 17 of the casing 11, is formed with a flange 20 on either of 105 the halves 9 and 10 which is adapted to close

the bottom of the portion 17 and the groove 16 is so formed in either half of the casing that the arm 1 and frame 6 can slide freely in same, into the position illustrated in Figure 2.

A stop or shoulder 21 is formed at the end of the groove 16 against which the edge of the frame 6 is adapted to engage to stop the rotation of the frame and arm in a downward direction.

The electro-magnetic coil B is of ordinary spool construction having a core opening 22 in which an armature 23 is adapted to operate longitudinally, when the coil is energized by an electric circuit or source of electrical energy. The armature 23 has an arm 24 pivotally secured to the forward end of the same and the arm 24 is pivotally connected to a pin 25 which operates in the slot 26 that is formed in the arm 24. The pin 25 is secured in the upper spoke 7 of the frame 6 and extends across the slot 27 formed in the spoke 7, in which the arm 24 is adapted to freely slide. A spring catch or bolt C is slidably secured in the frame 6 directly adjacent the upper spoke 7. The spring catch C is held in position by means of the spring 28 and is formed with an engaging end 29. The lower portion of the bolt is smaller in diameter than the upper portion and is adapted to carry a cylindrical collar 30 on its lower end which is freely held by the same.

A washer 31 is positioned between the collar 30 and the spring 28 against which the spring 28 is adapted to bear and the collar is freely and slidably held in the forwardly projecting portion 32 formed on the upper spoke 7 of the frame 6. The lower small end of the bolt 29 is formed with a transverse pin 33.

A bell crank lever 34 is pivoted at 35 to the lug 36 and the lug 36 is formed integral with a central or sleeve portion of the spider frame 6. The bell crank lever 34 has one end 37 held slidably between the pin 33 and the collar 30, the other end of 38 of the bell crank lever 34 is adapted to project upwardly in normal position, as illustrated in Figure 1 and is in position to be engaged by a transverse pin 39 which is rigidly secured to the outer end of the lever 24. The spring catch or bolt C is held in position so as to engage the notch 40 in the upper portion of the casing 11 by the spring 28 which is adapted to bear against the rear portion of the bolt 29 and against the washer 31 which rests on the lug or projection 32 when the parts are in the position illustrated in Figure 1. Thus the catch C is held into engagement with the notch 40 by means of the spring 28.

The electro-magnetic coil B is connected to an electrical circuit E which has a battery F or any other suitable source of electrical energy. (The battery being illustrated in

diagrammatic form). The coil B is connected to the electric battery F by means of the wires 41 and 42 and a push button or any suitable switch 43 is interposed in the wires 41 between the electro-magnetic coil B and the battery F.

The electric signal light D is connected to the electric battery F by means of the wires 44 and 45 and the wires 44 and 45 are secured to connections 46 and 47 which are rigidly held in the lower spoke 7 of the frame 6. The connections 46 and 47 are adapted to contact with spring fingers 48 which are fixed to the inner portion of the casing 11 when the signal arm is dropped in the position illustrated in Figure 2. One of the connections 48 is connected to a wire 49 which connects to one side of the battery F. The other connection 48 being connected to a wire 50 which connects to the battery wire 42 of the coil B, thus when the arm 1 is dropped in the position illustrated in Figure 2, the connections 46 and 47 will contact with the spring fingers 48 and form a complete circuit for the electrical signal light D, allowing the light to remain lighted while the arm is in the signalling position illustrated in Figure 2. When the arm 1 is drawn up in the position illustrated in Figure 1, the electrical connection with the battery F and the signal light is broken and the light goes out.

The armature 23 is formed with a cylindrical opening 51 in its rear end in which a coil spring 52 is positioned so as to bear against the head 53 which is formed on the pin 54. The pin 54 passes freely through the threaded plug 55 and is adapted to engage against the disk 56 which is positioned in the rear end of the core of the coil B and is secured to the casing 11 in any suitable manner. The pin 54 together with the spring 52 is adapted to position the armature 23 as will be hereinafter described. A releasing pin 57 having a head 58 secured thereto, is positioned in the upper portion of the casing 11 in the chamber 59 and a coil spring 60 is adapted to bear against the head 58 so as to tend to push the pin 57 outward. A threaded plug 61, through which the pin 57 passes freely, is adapted to hold the pin 57, together with its head 58, against disengagement from the chamber 59. The signalling device A is adapted to be clamped by any suitable device, not shown, in a convenient position on an automobile. The device A is used preferably to indicate the directions in which the automobilist desires to turn his machine. One or more of these signals can be used. It is preferred to use two signals, one on either side, so that one can indicate the turning in one direction and the other turning in the other direction.

When it is desired to use the signal device A, the switch or push button 43 is closed,

thereby sending electric energy into the electro-magnet and causing an inward pull on the armature 23. As the armature 23 pulls inwardly, the pin 39 which is connected to the end of the arm 24, will engage the end 38 of the arm 34 and pull downward on the spring bolt or catch C releasing the same from the notch 40, whereupon the spring pin 57 will kick the arm 1 over center of its pivot point and the arm with the signal light D will drop into the position illustrated in Figure 2.

When it is desired to dispense with the signal light D and bring the arm back to normal position as is illustrated in Figure 1, the switch or push button 43 is again operated and the electro-magnet will draw the armature 23 inward causing a pull on the pin 25 by the arm 24 and raising the arm 1 in the position illustrated in Figure 1 so the catch 29 will engage in the notch 40.

The spring pin 54 allows the armature 23 to enter the core of the magnet B when the electrical energy is applied during the raising of the signal arm 1 and the spring pin 54 will automatically force the armature 23 outward back to normal position as is illustrated in Figure 1 when the electrical energy is cut off from the coil B. The slot 26 allows the arm 24 to slide on the pin 25 and the end 37 of the bell crank arm pressing upward on the collar 30 against the spring 28 allowing the end 38 of the bell crank to be depressed so that the pin 39 can assume the position on the other side of the end 38, as is illustrated in Figure 1. Thus leaving the armature with the lever 24 and the pin 39 ready to release the catch 29 and the spring pin 57 depressed ready to automatically kick the arm 1 over center so as to again drop it into signalling position. The signalling operation can be repeated intermittently so as to cause the arm 1 to raise or lower as rapidly as may be desired.

The casing 11 is so constructed as to encase the working parts of the device A, and thereby gives a device which is of simple and neat appearance.

In the alternative construction illustrated in Figures 5 to 9 inclusive, the signalling arm 1 and the signal light casing 2 are of similar construction as that illustrated in the preferred construction, the light D being adapted to be encased in the casing 2. The magnetic coil B is not enclosed but is held in the body portion 70 in any suitable manner and a holding bracket 71 is formed on the end of the body 70. The bracket 71 has engaging fingers 72 which are adapted to hold the device A in a convenient place for operation. The electro-magnet B is connected to the electric circuit E by the battery wires 73 and 74. A switch 75 is interposed in the wire 74 between the battery F and the magnet B. The armature 23 of

the electro-magnet B is connected to an arm 76, said arm 76 being pivotally connected by means of the bolt 77 to the segment 78 which carries the arm 1 and is pivotally connected by means of the bolt 79 to the stationary segment 80 which is formed integral with the body portion 70. A spring catch 81 is pivotally secured at 82 to the segment 78 and is adapted to engage the shoulder 83 formed on the segment 80, when the arm 1 is in upright position. A coil spring 84 positioned about the rod 85 is adapted to hold the catch 81 into engagement with the lug 83. The upper end of the rod 85 has a head portion 86 rigidly secured thereto and the head portion 86 is formed with a slot 88 which is adapted to be pivotally and slidably connected to the catch 81 by means of the pin 87. The lower end of the rod 85 has an enlarged portion 89 formed thereon which is pivotally connected at 90 to the crank arm 91. The crank arm 91 is pivotally connected at 92 to the segment 78 and has an engaging end 93 which is adapted to be engaged by the pin 94 which is rigidly secured to the arm 76. Stops 95 and 96 are formed on the segment 78. The stop 95 is adapted to engage and depress one end of the pin 97 when the arm 1 is in upright position as illustrated in Figures 5 and 8 and the stop 96 is adapted to engage the other end of the pin 97 when the arm 1 is in the position illustrated in Figure 7. The arm 76 carries a spring 98 having one end secured to the arm 76 at 100 and the other end secured at 101 to the body 70 of the device A, being adapted to hold the arm 76 and the armature 23 in the position illustrated in Figure 5.

When it is desired to operate the signal illustrated in the alternative construction, the switch 75 is closed and the electric energy in the coil B will push the arm 76 outward. The pin 94 engages the crank arm 91 and pulls down on the catch 81 so as to release it from the stop or catch 83 and the spring pin 97 will kick against the stop 95 to push the arm 1 over the center of its pivot point and allow the arm to drop into signalling position as is illustrated in Figure 7.

Figure 6 illustrates the position of the lever 76 when the switch 75 is closed and the armature 23 pushes the lever 76 outward. When it is desired to raise the arm 1, the switch 75 is again closed and the electric energy in the coil B will push against the pin 77 and rotate the segment 78 on the bolt 79 to raise the arm 1 out of signalling position.

The construction illustrated in Figures 10 and 11 is practically the same mechanical and electrical construction as that illustrated in Figures 1, 2 and 3. The coil B is held in the casing which is formed in two halves 9 and 10 (the portion 9 only being shown). The coil B is connected to the signal arm 1

in the same manner as illustrated in Figure 1 and the arm 1 is adapted to be released into signalling position in a similar manner as the construction illustrated in Figure 1 by the coil B. The frame 6 which carries the signal arm 1 is pivotally secured to the shaft 8 in the same manner as the construction illustrated in Figure 1. A projecting stop or shoulder 105 is formed on the frame 6 which projects forward from the lower spoke 7 of the frame 6 and is adapted to strike the shoulder or stop 106 which is formed on the inner portion of the casing 9 and is similar to the shoulder 21. A coil spring 107 is fixed on one end by means of the screws 108 to the spoke 7 of the frame 6 and has a disk-shaped bumper 109 secured to its free end so that when the arm 1 is dropped into signalling position, the bumper 109 will strike against the shoulder 106 compressing the spring 107 as is illustrated in Figure 11. Thus the springs 107 will relieve the jar on the arm 1 as it drops into signalling position and will also tend to force the arm up again toward the position illustrated in dotted outline in Figure 11.

The electric wiring illustrated in diagrammatic form in Figure 10 illustrates an electric battery R connected to the coil B by means of wires 110, 111 and switch 112 so that when the switch 112 is closed, electrical energy will be introduced into the coil B to operate the armature 23 and release or raise the arm 1 into signalling or out of signalling position respectively, in the same manner as illustrated and described by the construction in Figures 1 and 2.

Brushes 113 are rigidly secured to one side of the casing which encloses the working parts of the device A and the coil B, the brushes 113 being positioned in the forward part of the casing where the arm 1 with its frame 6 is pivoted. The brushes 113 are secured to the insulating block 114 and the block 114 is secured by the screws 115 to the casing 10 so that the brushes 113 are held insulated from each other and from the casing. The brushes 113 are illustrated in Figures 10 and 11 in dotted outline. A contacting piece or bar 116 is rigidly secured to one side of an insulated arm 117 and the arm 117 is rigidly secured to the pin or horizontal bolt 118. The bolt 118 is rigidly secured to the inner surface of the frame 6 by means of the screws 119 which pass through the flange 120 in which the bolt 118 is rigidly secured. The arm 117 is so formed as to have its upper edge project above the upper edge of the contact bar 116 and is of the same width as the bar 116, thus the bar 116 is fixed adjacent the upper portion of the arm 117 and is insulated on one side by the arm. The lower portion of the arm 117 projects below the pivot point or bolt 118 and is formed with an opening 121 in which one

end of coil springs 122 is engaged and the other ends of the springs 122 are secured to the frame portion 6 so that the springs 122 will normally hold the arm 117 in a perpendicular position as is illustrated in Figure 12, but allowing the arm 117 together with the contact bar 116 to swing into the position illustrated in dotted outline, returning the arm 117 into perpendicular position.

The brushes 113 are connected to the coil B and the battery R by means of the wires 123 and 124. A suitable switch 125 is interposed in the wire 123 so that when it is desired, the switch can be readily closed or opened. The purpose of the brushes 113 with their connecting wires is to keep the signal arm 1 with its light D moving up and down or oscillating on its pivot point 8 after it has been released into signalling position. This is accomplished by closing the switch 125 and then momentarily closing the switch 112 similar to the operation of the switch 43 in Figure 2, thereby sending electrical energy through the coil B and releasing the signal arm 1 into position illustrated in Figure 11. When the signal arm 1 drops into the position illustrated in Figure 11, the arm 117 will be carried past the brushes 113 and the arm 117 will be moved into one of the dotted positions illustrated in Figure 12, allowing the brushes 113 to pass over the topmost portion of the arm which projects above the contact bar 116 and preventing any electrical contact between the bar 116 and the brushes 113. The stops 105 and 106 limit the downward movement of the signal arm 1 and the compression of the spring 107.

When compressed, the spring 107 will tend to force the arm 1 away from the stop 106, causing the contact bar 116 to contact with the brushes 113 on the backward movement of the arm, closing the electrical circuit through the battery R and coil B and causing the coil B to pull upward momentarily on the signal arm. The contact of the brushes 113 on the bar 116 being only momentarily and not allowing sufficient time or energy for the coil B to pull the arm back out of signalling position but raising the signalling arm into the position illustrated in dotted outline in Figure 11, whereupon the brushes 113 disconnect from the contact bar 116 and the circuit is broken and the arm will again drop by gravity back to the position illustrated in full lines in Figure 11. The spring 107 will force the contact bar 116 against the brushes 113 again, thereby repeating the operation of the coil in pulling the signal arm upward.

In the operation of the construction illustrated in Figures 10 and 11, the signal arm can be oscillated up and down after it is dropped into signalling position, it

being obvious that the arm will oscillate up and down until the switch 112 is closed long enough to allow the armature 23 of the coil B to pull the signal arm 1 up out of signalling position, as illustrated in Figure 10. Should it be desired not to have the arm reciprocate up and down after it has dropped into signalling position, the switch 125 could be left open and the signal arm 1 operated only by the switch 112, the signal arm and device A operating in the same manner as described in the construction illustrated in Figures 1 and 2. By means of the construction illustrated in Figures 10 and 11, the signal arm is operated so as to reciprocate automatically up and down after it has been dropped into signalling position by means of the switch 112, it being evident that it is necessary to close the switch 112 only momentarily when dropping the arm into signalling position but to hold the switch 112 closed long enough to allow the coil B to raise the arm when it is desired to raise the arm out of signalling position. The coil spring 107 causing the arm to rebound sufficiently to cause the brushes 113 to contact with the contact bar 116. This contact is only momentarily so that the coil B does not obtain sufficient energy to raise the arm out of signalling position but tends to jerk the arm up as far as the position illustrated in dotted outline in Figure 11, whereupon the arm again drops into its lower most position. This reciprocating continues automatically until the switch 112 is again closed long enough to allow the armature 23 and coil B to raise the arm 1 out of signalling position. It is obvious that the construction illustrated in Figures 10, 11 and 12 is not materially different from that illustrated in Figures 1, 2, 3, and 4 but a secondary electrical circuit is connected with the battery or source of energy which has means to keep the arm reciprocating up and down automatically when it is in signalling position.

It is an important feature that in operating the preferred or alternative construction of the device A that the switches 32, 75 and 112 are closed momentarily in dropping the signal giving the parts a chance to be released quickly and allowing the arm 1 with its connecting parts to draw or push the armature 23 into position so that when electric energy is again sent through the electro-magnet B, the armature will pull or push the arm 1 up out of signalling position. It is understood however, that it is necessary to hold the switches 43, 75 and

112 closed for a longer period of time when it is desired to raise the signal arm out of signalling position to give the coil sufficient energy and time to raise the signal arm.

65

It is also an important feature that the signalling device A is operated by one electro-magnet into either signalling or out of signalling position and the simplicity of the co-operating parts, makes the device practical. In both the preferred and alternative constructions, the spring catch is released and the signal arm 1 dropped into signalling position. The same magnet and co-operating parts drawing the arm back out of signalling position, thus by closing the switches 43, 75 or 112, the arm 1 will automatically drop into signalling position and by closing the switches again, the arm 1 will be drawn out of signalling position. The device operates quickly and perfectly.

80

While I have illustrated particular forms and construction of parts, I desire to have it understood that I do not wish to confine myself to the particular construction illustrated, but that the invention can be carried out by other means and applied to other uses within the scope of the following claims:

85

1. A direction indicator comprising a pivoted signal arm adapted to normally assume a vertical position, a latch for holding said signal arm in its normal position, means including a slotted link and a slidable member adapted to release said latch upon movement in one direction, a member secured to said signal device adapted to slide along the slot in said link by means of which said signal device may be returned to its normal position on moving said slideable member in the same direction.

90

2. In a device of the class described, having a signal arm, a single coil electro-magnet having its armature connected to said arm, means for raising or releasing said arm by said electro-magnet and means for automatically keeping said arm oscillating without raising it out of horizontal signalling position, substantially as described.

95

3. In a device of the class described, having means for electrically raising or releasing a pivoted signal arm by means of one electro-magnetic coil connected to an electrical source of energy and means for sending electric impulses intermittently into said coil to automatically oscillate said arm back and forth while in horizontal signalling position, substantially as described.
